CLAIM

The ornamental design for a beverage dispenser, as shown and described.

DESCRIPTION

FIG. 1 is a front perspective view of a beverage dispenser in accordance with my new design.

FIG. 2 is a front elevation view thereof.

FIG. 3 is a back view thereof.

FIG. 4 is a first side view thereof.

FIG. 5 is a second side view thereof.

FIG. 6 is a top view thereof.

FIG. 7 is a bottom view thereof.

FIG. 8 is a front perspective view of an alternative embodiment for a beverage dispenser in accordance with my new design.

FIG. 9 is a front view thereof.

FIG. 10 is a back view thereof.

FIG. 11 is a first side view thereof.

FIG. 12 is a second side view thereof.

FIG. 13 is a top view thereof; and,

FIG. 14 is a bottom view thereof.

The broken lines depict portions of the beverage dispenser that form no part of the claimed design.

1 Claim, 14 Drawing Sheets
